NARROW FRAME SCREEN DOOR LATCH

Andrew Erkkila, Fitchburg, Mass., assignor to Independent Lock Company, Fitchburg, Mass., a corporation of Massachusetts

Application February 20, 1953, Serial No. 338,077

5 Claims. (Cl. 292—169)

This invention relates to screen door latch sets and more particularly to screen door latch sets having a short back set. My invention more specifically concerns itself with the problem of installation of a latch on door frames, such as screen doors or, more recently introduced, screen and storm doors made of aluminum frames in which the stiles thereof are of narrow dimensions, to hold replaceable screens or glass lights.

Efforts by me to embody in a frame for a door of the character described on a simple spindle actuated latch bolt have encountered dimensional problems in an effort to retain the proper operating conditions. Due to the extremely short backset the incorporation of a spring to project the latch bolt of requisite stiffness to orient a lever handle against sagging to a normal position has not been found successful with constructions heretofore employed to meet the requisite spring rigidity for spindle operation while affording independent yieldability, assuring long life.

Accordingly, it is an object of my invention to provide a latch assembly or door set for narrow stiles involving short backsets of the spindle in which adequate spring compressibility for spindle operation and knob orientation is combined with soft nose yieldability for independent latch bolt depression. Thus, it is an object of this invention to provide a screen door set having a screen projected latch bolt actuated by double compression springs, one which has the requisite stiffness to orient the spindle to a normal position, thereby not only to project the latch bolt in the strike plate, but to maintain the spindle and lever handle carried thereby against sagging in a predetermined position, but also includes a soft spring reaction to depression of the latch bolt, as when it independently is depressed by the latch being cammed by the strike plate and to combine these features in a casing fitting within a narrow stile of a door and having a relatively short backset.

To attain these objects and such other objects as may appear herein or be hereinafter pointed out, reference is made to the accompanying drawing, forming a part hereof, in which—

Figure 1 is a transverse section showing a door lock set in accordance with my invention;

Figure 2 is a magnified section taken on the line 2—2 of Figure 1;

Figure 3 is a view similar to Figure 2 with the latch bolt independently depressed by the strike plate;

Figure 4 is a view similar to Figure 2 showing the latch bolt in spindle retracted position;

Figure 5 is a section taken on the line 5—5 of Figure 2;

Figure 6 is a section taken on the line 6—6 of Figure 2;

Figure 7 is a section taken on the line 7—7 of Figure 4;

Figure 8 is a fragmentary section through the latch bolt showing a position of the spindle for installation.

Making reference to the drawing, I illustrate my invention in connection with a fragment of a door 10 having a tubular stile 11. Such frames may be made of sheet metal and preferably extruded aluminum, serving the double purpose of both a storm door during the winter and as a screen door during the summer.

The stile 11 has a closure edge 12 provided with a channel 13 in which there is seated the end plate 14, to which is affixed the latch casing 15. The latch casing is tubular and has an abutment wall desirably shown as a closed end wall 16 and an open end 17 adjacent the supporting end plate 14. The latch is assembled into the casing 15 through the opening 17 and for this purpose there is first introduced into the casing a relatively soft coiled compression spring 18 which peripherally is guided adjacent the wall 19. Concentric with the spring 18 there is introduced a heavy coiled compression spring 20 which is maintained centrally of the casing on the lug 21 affixed to the end wall 16.

With the soft and stiff springs 18 and 20 respectively introduced telescopically into the casing through the mouth 17, there is then inserted in the casing the latch bolt assembly 22 comprising the latch bolt 23 carrying rearwardly thereof the latch shank 24, having spaced branches 25, 25, comprising guide arms joined to the latch bolt by the ring 26, seated within the annular slot 27 and longitudinal extension slot 27a formed in the latch bolt 23 to lie flush with the latch bolt and make a sliding fit within the casing. The guide arms 25 extend rearwardly and are joined to each other by the end disk 28, having an aperture 29 centrally thereof through which the stiff spring 20 projects.

Slidably guided between the guide arms 25, 25 there is mounted the cam follower block 30 having rearwardly thereof a boring 30a into which the stiff spring 20 is centered after passing through the aperture 29 of the end disk 28. The follower block 30 is cylindrical, slidably to fit within the casing, and is formed with guide slots 31 in which the guides 25 are mounted for relative slidable movement of the cam follower and guide arms 25.

With this assembly so inserted within the casing, a set screw 32, having a guide pin 33, is projected through the casing to engage the retainer slot 34 formed in the latch bolt. The slot 34 has its end walls 35 and 36 spaced from each other to limit the outward projection of the latch bolt 23 when the end wall 35 engages the pin 33, and to limit the inward movement of the latch bolt when the wall 36 engages the pin 33, assembly being effected by depressing the latch bolt 23, in which condition the set screw 32 is driven home to engage the slot 34. Upon seating the set screw 32, the latch bolt assembly is projected outwardly and under the combined influence of the soft spring 18 and the hard spring 20. The cam follower 30 is slidably guided in the casing 15 to float freely along the shank 20, to be guided non-rotationally by the arms 25 in close adjacency to the apertures 37 through the casing, and is likewise accessible when mounted as shown in Figure 1 in alignment with the bores 38 formed in the plates 39 of the stile.

Adjacent the plates 39 there are provided escutcheons 40 having bearing collars 41 arranged rotationally to receive and to center the shank 42 of the knob 43 at one end. The knob 43 carries a spindle 44 connected to the knob by the set screw 45. The spindle 44, adjacent its center, has a rock shaft cam 46 and a follower seat 47 to receive the nose 48 of the cam follower 30.

When the casing assembly has been positioned in the door stile to align the apertures 37 with the bores 38, the latch bolt is depressed to move the same from the position shown in Figure 2 to the position shown in Figure 3, thereby depressing the disk 28 to clear the apertures 37. In this position the spindle 44 is projected through the escutcheon 40 to enter the aperture 37. The spindle is provided with a chamfered nose 49 to wedge the cam follower block 30 against the pressure of the stiff spring 20 and to thread the shank through the casing and the opposed frame boring 38a on the opposite face of the stile through the escutcheon 40, to be engaged by the lever handle 43a and to seat the shank 42a thereof in the escutcheon 41a.

In this position the cam 46 is seated upon the follower 30, to nest the nose 48 in the cam seat 47. Thereupon the set screw 51 is driven home in position in a manner well understood.

By the assembly described, it will be observed that when the latch bolt 23 is released it will be projected through the strike 52. For withdrawal of the latch bolt, the spindle 44 is oscillated by turnknob operation, which serves to cam the cam 46 against the angular faces of the nose 48 of the cam follower, drawing with it the latch bolt assembly and projecting the cam follower against the disk 28 and the follower block 30 against the spring 20. The latch bolt assembly thereby is depressed against the combined spring resistance of the springs 18 and 20. Upon release of the knob, the cam follower nose engages one of the diametrically opposed wings 53, 53 of the cam, to rock the spindle to its normal position under the biasing action of both springs 18 and 20, until the nose 48 is seated in the cam seat 47.

When the latch bolt 23 has been withdrawn and then released for opening the door, the door may be swung into closed position without manual guidance or manual retraction of the latch bolt.

In the projected position, as shown in Figures 1 and 2, the latch bolt may, upon closing the door, engage the strike plate, depressing the latch bolt by the camming action of the nose 54 of the strike plate. Inward projection of the latch bolt through the arms 25 against the disk 28 is against the resilient resistance of the soft coiled spring 18, while the stiff spring 20 retains the follower block 30 in engagement with the cam 46, as more clearly shown in Figure 3.

The floating, sliding position of the cam follower plug 30 thereby leaves the latch bolt assembly for independent depression upon striking the strike plate with minimum resistance, without interfering with the full throw necessary for securing retraction. Likewise, the projecting influence of both the stiff and soft springs is obtained for the latch bolt as well as to orient the spindle and lever handle carried to a proper position without an undue extension of the casing, thereby permitting a backsetting of the center line of the spindle within narrow dimensional limits and making this assembly possible in narrow stiles especially metal tubular frames.

Thus, it will be observed that all of the benefits of stiff spring projection and non-sagging lever handle orientation and soft nose reaction are obtained in very compact form, to secure in a novel assembly all of the benefits of more extensive casing assemblies.

It will be understood that locking means for the spindle 44 may be mounted in either of the escutcheons which may be extended to the outer face of the door.

Having thus described my invention and illustrated its use, what I claim as new and desire to secure by Letters Patent is:

1. In a latch having a latch bolt casing, a latch bolt assembly including a latch bolt shank comprising spaced branches guided in said casing adjacent the casing walls; an independent follower guided by the branches of said shank, independent spring projecting means for said latch bolt assembly including one for said follower and another

for said latch bolt shank, a rock shaft spindle positioned between said branches and transversely extending through said casing to have its opposite ends project through said casing, to which ends knob means are affixed, said rock shaft spindle, at its intermediate portion, having camming means cooperating with said follower, to retract said latch bolt upon oscillation of said rock shaft spindle by sliding said follower, said latch bolt being independently depressible.

2. In a latch, a latch casing including a latch bolt shank having spaced branches guided by the walls of said casing, a follower guided by the branches of said shank, independent springs for projecting said latch bolt and follower concentrically nested, a rock shaft spindle extending between said branches and through said casing, with the opposed ends of said rock shaft spindle projecting at opposite sides of said casing, said rock shaft spindle, at its intermediate portion, having a camming member engaging said follower, said follower and camming member having cooperative engaging means whereby oscillating said rock shaft spindle will retract said follower and shank against the influence of both springs, said latch bolt being independently depressible against one of said springs while the other spring maintains the follower in spindle engaging position.

3. In a latch having a short backset comprising a tubular latch casing closed at one end, an end plate supporting the casing adjacent the open end, a pair of concentrically arranged compression springs in said casing engaging the closed end thereof, a latch bolt assembly projected by said springs and guided by said casing, said latch bolt assembly including a shank having spaced branches, a follower guided between said branches, said follower being spring projected by one of said springs, said shank being projected by the other of said springs, with independent relative movement between the shank and follower, a rock shaft spindle transversely positioned through said casing between said branches having camming means engaging said follower for conjoint retraction of said follower and latch bolt, the latch being independently depressible against the action of one of said springs while the other spring maintains the follower in spindle engaging position.

4. In a latch having a short backset, a tubular casing having at one end a closed end wall and a guide opening at the other end, a pair of compression springs bearing against said end wall concentrically positioned on said end wall and of different stiffness, a latch bolt assembly guided by said casing under the influence of both springs guided through said open end, said latch bolt assembly having a shank comprising wall engaging branches extending in said casing under the influence of the weaker of said springs, a floating follower guided by said shank, said follower being spring projected by the stiffer of said compression springs, a rock shaft spindle extending through said casing between said branches having a camming portion actuating said follower whereby, upon rocking said spindle, the latch bolt is retracted against the influence of both compression springs and to project the latch bolt and follower under such influence, the latch bolt being independently depressible against the influence of the softer of the compression springs.

5. In a latch for a short backset comprising a tubular casing, a wall at one end and a guiding opening at the other, concentric compression springs supported against said end wall, a latch bolt assembly guided through said opening by said casing, a shank extending from said latch bolt having spaced guide arms, a pressure disk joining said guide arms engaged by one of said springs, a follower floating between said guide arms under the influence of said second spring and projectible through said pressure disk to contact said follower and a rock shaft knob spindle extending through said casing between said guide arms having a camming portion engaging said follower, cooperative nose and seat portions on said fol-

lower and cam whereby the latch bolt assembly is spring projected under the influence of both springs, the follower being under compression of said second spring to orient the rock shaft and said latch bolt being independently depressible against the influence of only one of said springs.
